LOCK

Charles Kemp, New York, N. Y., assignor to
Kemp Lock Inc., New York, N. Y., a corpora-
tion of New York

Application October 11, 1930, Serial No. 487,969

16 Claims. (Cl. 70—74)

This invention relates to locks.

The type of lock to which this invention is directed is disclosed in my co-pending application Serial No. 483,174, filed September 20th, 1930, and it is the object of this invention to generally improve and simplify the same.

Another object of this invention is to provide in a lock of the character described wherein a pair of vertical bolts are moved outwardly away from each other into engagement with a keeper, simultaneously with the projection of a horizontal bolt, invertible actuating mechanism for converting the lock for use with vertical bolts adapted to be moved inwardly toward each other upon projection of said horizontal bolt.

A further object of this invention is to provide a neat, compact and strong lock of the character described which shall comprise few and simple parts, which shall be of economical construction, smooth and positive in operation, which shall be easy to assemble and disassemble and which shall yet be practical and efficient to a high degree.

Other objects of this invention will in part be obvious and in part hereinafter pointed out.

25 The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a rear elevational view of a lock embodying the invention with the rear cover plate removed;

Fig. 2 is a cross-sectional view taken on line 2—2 of Fig. 1;

Fig. 3 is a cross-sectional view taken on line 40 3—3 of Fig. 1;

Fig. 4 is a front elevational view of a lock embodying the invention provided with vertical bolts adapted to be moved inwardly toward each other upon projection of the horizontal bolt, and showing parts of the lock structure of Fig. 1 in reversed or inverted position for coaction with said vertical bolts.

Fig. 5 is a cross-sectional view taken on line 5—5 of Fig. 1; and

50 Fig. 6 is an end elevational view of the lock casing.

Referring now in detail to the drawings, 10 designates a portion of a door on which is mounted, adjacent the vertical edge 11 thereof, a lock 12 here shown as carrying a plurality of bolts

adapted to cooperate in the manner hereinafter described with a strike or keeper 14 attached to the door jamb 15. The lock 12 comprises a casing 12a having a front wall 18, top and bottom walls 19 and 20, an end wall 21 remote from the edge 11 of the door, and a second end wall 22 disposed adjacent said edge of the door. The casing may be secured to the door in any suitable manner, as for instance, by means of screws or the like fastening members extending through openings 24 formed in extending portions of the casing adjacent the rear edge 25 thereof. The top and bottom walls 19 and 20 and the end wall 21 are formed with an internal ledge or shoulder 26 adjacent said rear edge 25 thereof, for seating 70 a cover plate 27. Said cover plate may be secured to said casing in any suitable manner, as for instance by means of screws extending through threaded openings 30 in bosses 31 integrally formed with the top and bottom walls 19 75 and 20 of said casing 12a. The casing 12a furthermore may be formed with symmetrical aligned wall portions 32 extending outwardly from said top and bottom walls 19 and 20 and disposed parallel to the end wall 22. Extending 80 outwardly from said top and bottom walls 19 and 20 are walls 33 parallel to the front wall 18 and joining the walls 32 and 22. It will be noted that the walls 32, 33 and 22 form with the cover plate 27 a pair of tubular openings 35 at the top and 85 bottom of the casing adjacent the front wall 22 and communicating with the interior of the casing.

For the purpose hereinafter appearing, the front wall 18 is formed with a pair of integral 90 parallel ledges or guides 36, 37. The boss 31 extending from the bottom wall 20 may likewise be provided with a flat surface 39 parallel to said steps 36, 37. Slidably mounted within the casing 12a and guided by and between the parallel step 37 and said surface 39, is a member 40 having a plate portion 41 parallel to said front wall 18. Said member 40 is provided with an extension 41a resting on and guided between the steps 36, 37. Extending from said plate 41 at right angles thereto is an integral plate portion or wall 42 disposed parallel to the end wall 22 of the casing. 100

It will be noted that said member 40 may be reciprocated within the casing 12a. The front wall 18 of the casing may be provided adjacent the top and bottom walls 19 and 20 thereof with parallel ledges 40a and 40b, supporting and serving as guides for the end portions 42a and 42b of said wall 42. 105

Means is provided for reciprocating said mem- 110

ber 40 within the casing. To this end, the front wall 18 of the casing is formed with an integral boss 50 having a bore rotatably receiving a finger knob 51 projecting into the casing. Fixed to the 5 inner end of the knob is an arm 52 having a pin 52a at the outer end thereof pivoted to one end of a link member 53, said link being pivotally attached at the other end thereof to pin 54 fixed to said plate 41.

10 It will now be seen that upon rotating the knob 51, the arm 52 is rotated therewith for moving the link 53 and causing sliding movement of the member 40. Any suitable key control mechanism 56 may be mounted on a cover plate 27 and provided with an arm 57 substantially contacting the inner side of said cover plate and provided with a forwardly extending lug 58 pivoted to a rearwardly extending portion 53a of said link 53. Thus, upon turning the key within the mechanism 56, the arm 57 is rotated and the lug 58 actuates the link 53 for translating said member 40.

15 A coil spring 59 may be mounted on a rearward extension of said pin 54, and provided with end extensions 60 engaging portion 53a of the link 53 and the plate portion 42 for normally urging said member 40 toward the end of its stroke in either direction. The wall 42 is provided with a pair of spaced symmetrical openings 61 and the front 20 wall 22 of the casing is provided with a pair of openings 62 aligned with said openings 61, for the purpose hereinafter appearing.

25 Mounted on said wall 42 are a pair of horizontal similar bolts 63 and 64 having reduced portions 63a and 64a extending thru said openings 61, the end portions of said bolts being slidably disposed within the openings 62 in end wall 22. Extending rearwardly from and fixed to plate portion 41 of said member 40 are pins 65 and 66, 30 said pins extending thru said portions 63a and 64a of said bolts 63, 64, respectively, for fixing said bolts to said member 40.

35 It will thus be seen that the bolts 63, 64 are fixed to member 40 by means of pins 65, 66 respectively, and that said bolts may be projected from the casing or retracted into the casing upon actuation of the finger knob 51 or the key actuating mechanism 56.

40 As illustrated in Fig. 1 of the drawings, the lock is provided with a pair of vertical bolts 70, 71 adapted to be moved outwardly away from each other simultaneously with the projection of the horizontal bolts 63, 64. Said bolts 70 and 71 are symmetrically disposed with respect to one 45 another and are provided with portions 72 and 73 respectively slidably extending within the tubular openings 35 of the casing 12a. Extending inwardly from said portions 72, 73 are flat plate portions 74, 75 having pins 74a and 75a fixed thereto adjacent the inner ends thereof and projecting rearwardly toward said cover plate 27. Mounted within the casing adjacent the cover 50 plate 27 and disposed between said cover plate and the wall 42 of member 40 are a pair of symmetrically disposed plate members 80 and 81 to be described in detail hereinafter. Said members 80 and 81 are provided adjacent one end thereof, with substantially oval shaped slots 82 and 83 respectively, pivotally and slidably receiving said pins 74a and 75a. Said members 80, 55 70 are furthermore pivoted adjacent the opposite end to the cover plate 27 by means of pins 84, 85 fixed to the inner side of said cover plate. Said members 80 and 81 are also provided with elongated inclined slots 87 and 88 respectively,

58 slidably receiving the upper ends of the pins 65, 66. As shown in Fig. 1, the slots 87, 88 are inclined inwardly toward each other and toward end wall 22 and are, further symmetrically disposed with respect to the longitudinal mid-section of the casing. It will thus be seen that upon actuation of the knob 51 for moving the member 40 to the right, as seen in Fig. 1, the bolts 63, 65 will be projected from the casing and the pins 65, 66 will move within the slots 87, 88 for causing pivotal movement of the members 80, 81 about pins 84, 85, away from one another. Such movement of said members 80, 81 will cause outward sliding movement of the bolts 70, 71 away from each other, due to the pin and slot connections 74a, 82 and 75a, 83, into engagement with keeper 14. Said members 80, 81 thus have cammed connections with the bolts. Obviously, actuation of the knob 51 in the opposite direction will cause member 40 to slide to the left for retracting the bolts 63, 65 and causing pivotal movement of the members 80, 81 about the pins 84, 85 inwardly toward each other. This action will move the bolts 70, 71 inwardly toward one another for disengaging the same from the keeper 14. Said bolts 70, 71 are provided with portions 90 and 91 respectively, parallel to each other and adapted to overlap the door jamb. Said bolts are furthermore provided with outwardly extending aligned portions 92 and 93 adapted to engage within suitable openings in said keeper 14. Said keeper obviously is provided with suitable openings for receiving the forward ends of the horizontal bolts 63, 64 whereby both horizontal and vertical bolts may be simultaneously moved into engagement with or out of engagement from said keeper.

100 In Fig. 4, the bolts 100 and 101 are U-shaped and are provided with portions 102 and 103 extending inwardly toward each other and adapted to engage within openings 104 and 105 respectively, of a keeper 106. The pivoted members 80 and 81 however, are inverted from the position shown in Fig. 1 so that the inclined slots 87 and 88 will diverge away from the longitudinal mid-section of the casing and toward the end wall 22 instead of toward said mid-section and toward said end wall, as shown in Fig. 1. Said members 80 and 81 are pivoted to the cover plate 27 by means of said pins 84, 85 and are also provided with slots 82 and 83 slidably receiving there-through, pins 107 and 108 extending rearwardly from inner portions of the bolts 100 and 101.

105 It will now be understood that upon projection of the bolts 63, 64 the members 80 and 81 will be pivotally moved toward each other due to the action of the pins 65 and 66 within said slots 87, 88. This movement of the members 80 and 81 will cause the U-shaped bolts 100 and 101 to move inwardly toward each other into engagement with the strike 106, the horizontal bolts 63 and 64 simultaneously moving into engagement within openings 109 and 110 in said keeper. Actuation of the finger knob in the opposite direction will cause retraction of the horizontal bolts 63, 64 and movement of the pivoted members 80, 81 away from each other spreading the bolts 100 and 101 and disengaging the portions 102 and 103 thereof from the strike 106.

110 It will thus be seen that for adapting the lock shown in Fig. 1 for use with bolts to be moved inwardly toward each other upon projection of the horizontal bolts, the pivoted members 80 and 81 need merely be inverted in the manner illustrated and described, and the U-shaped bolts 100 and 101 substituted for the bolts 70 and 71. 115 120 125 130 135 140 145 150

It will thus be seen that there is provided a device in which the several objects of this invention are achieved, and which is well adapted to meet the conditions of practical use.

6 As various possible embodiments might be made of the above invention, and as various changes might be made in the embodiment set forth, it is to be understood that all matter herein set forth or shown in the accompanying drawings is to be interpreted as illustrative and not in a limiting sense.

Having thus described my invention, I claim as new and desire to secure by Letters Patent:

1. A door lock comprising a casing having an end wall formed with an opening and adapted to be disposed adjacent the edge of the door, a member slidably mounted within said casing, a bolt slidably extending within said opening, a member pivoted to said casing and having a slot inclined to said bolt, and a pin fixed to said slidably mounted member, received within said slot, said pin extending through said bolt for non-rotatably fixing said bolt to said slidably mounted member.

25 2. A door lock comprising a casing having an end wall formed with an opening and adapted to be disposed adjacent the edge of the door, a member slidably mounted within said casing, a bolt fixed to said member and slidably extending within said opening, a member pivoted adjacent one end thereof to said casing and having a slot inclined to said bolt, a pin fixed to said slidably mounted member, received within said slot, a second bolt slidably mounted on said casing transversely of said first bolt, said pivoted member having a slot adjacent the opposite end thereof, said second bolt having a pin projecting through said second slot.

35 3. A lock comprising a casing, a member slidably mounted in said casing having a wall portion formed with an opening, a bolt having a portion projecting thru said opening, said member having a second wall portion extending at right angles to said first wall portion, and a pin fixed to said second wall portion and extending thru said portion of said bolt for non-rotatably fixing said bolt to said member.

4. A lock comprising a casing, a member slidably mounted in said casing having a wall portion formed with an opening, a bolt having a portion projecting thru said opening, said member having a second wall portion extending at right angles to said first wall portion, a pin fixed to said second wall portion and extending thru said portion of said bolt for fixing said bolt to said member, a plate member pivoted to said casing and having an elongated slot, said pin slidably extending into said slot.

5. A lock comprising a casing, a member slidably mounted in said casing having a wall portion formed with an opening, a bolt having a portion projecting thru said opening, said member having a second wall portion extending at right angles to said first wall portion, and a pin fixed to said second wall portion and extending through said portion of said bolt for fixing said bolt to said member, a member pivoted to said casing and having an elongated slot, said pin slidably extending into said slot, and a second bolt slidably mounted on said casing and having a pin and slot connection with said pivoted member.

6. In a lock, a casing having a front wall and an end wall, a rear cover plate for said casing, a member of angular cross-section mounted for reciprocation on said casing, said member having

a wall portion parallel to and disposed adjacent said front wall, and a wall portion extending at right angles from said first wall portion and disposed parallel to said end wall, said second wall portion and said end wall being formed with aligned openings, a bolt having a reduced portion extending through said opening in said second wall portion, said bolt being slidably received in the opening in said end wall, a pin fixed to said first wall portion and extending through said reduced portion of said bolt, and a member pivoted to said cover plate and having a slot slidably receiving an end portion of said pin.

7. In a lock, a casing having a front wall and an end wall, a rear cover plate for said casing, a member of angular cross-section mounted for reciprocation on said casing, said member having a wall portion parallel to and disposed adjacent said front wall, and a wall portion extending at right angles from said first wall portion and disposed parallel to said end wall, said second wall portion and said end wall being formed with aligned openings, a bolt having a reduced portion extending through said opening in said second wall portion, said bolt being slidably received in the opening in said end wall, a pin fixed to said first wall portion and extending through said reduced portion of said bolt, a member pivoted to said cover plate and having a slot slidably receiving an end portion of said pin, and a bolt slidably mounted in said casing transversely of said first bolt, and having a pin and slot connection with said pivoted member.

8. In combination with a door, a lock for said door, comprising a casing mounted on said door, a horizontal bolt slidably mounted on said casing, a vertical bolt having a portion slidably received within said casing and extending therefrom, and a portion normally extending exteriorly of said casing and projecting beyond the edge of said door, and a portion parallel to said first portion and adapted to engage a strike mounted on the door jamb, a member pivoted to said casing and having a pin and slot connection with said horizontal bolt, and a cammed connection with the first portion of said vertical bolt.

9. A lock comprising a casing, a horizontal bolt slidably mounted therein, a pair of oppositely extending symmetrical, vertical bolts having portions slidably extending through said casing and portions extending exteriorly of said casing and parallel to said first portions, and a pair of symmetrical members each pivoted adjacent one end thereof to said casing, said members having slots in intermediate portions thereof inclined to the horizontal mid-section of the casing, pins fixed to said horizontal bolt engaging within said slots, said pivoted members having cammed connections adjacent the outer ends thereof, with said first portions of said vertical bolts.

10. A lock comprising a casing, a horizontal bolt mounted therein, a pair of vertical bolts slidably mounted on said casing, and a pair of symmetrical members each pivoted adjacent one end thereof to said casing, said members having slots in intermediate portions thereof inclined to the horizontal mid-section of the casing, pins fixed to said horizontal bolt engaging within said slots, said members having cammed connections adjacent the outer ends thereof with said vertical bolts, said pivoted members being adapted for pivotal connection to said casing in inverted position, and the slots therein being adapted to receive the pins fixed to the horizontal bolt in said inverted position.

11. A lock comprising a horizontal bolt mounted therein, a vertical U-shaped bolt having an arm slidably mounted in said casing, and an arm extending beyond said casing, a member pivoted 5 to said casing and having a pin and slot connection with said horizontal bolt and being operatively connected to said first arm of said U-shaped bolt, said bolts and member being arranged for moving said U-shaped bolt inwardly 10 toward the mid-section of said casing upon projecting said horizontal bolt. 15
12. A lock comprising a casing, a horizontal bolt mounted therein, a U-shaped bolt having an arm slidably mounted within said casing, and an arm extending beyond said casing, a member pivoted adjacent one end thereof to said casing, 20 said member having an inclined slot, a pin on said horizontal bolt engaging within said slot, the opposite end of said pivoted member engaging said first arm of said U-shaped bolt whereby said U-shaped bolt may be moved inwardly upon projecting said horizontal bolt. 25
13. A lock comprising a casing, a horizontal bolt mounted therein, a pair of symmetrically disposed oppositely extending U-shaped bolts each having an arm slidably mounted in said casing, and an arm extending beyond said casing, and a pair of symmetrical members each pivoted adjacent one end thereof to said casing, said members having slots at intermediate portions thereof, said slots being inclined outwardly from the horizontal mid-section of the casing, pins fixed to said horizontal bolt engaging within said slots, the opposite ends of said members engaging 30 said first mentioned arms of said U-shaped bolts 35 for moving said U-shaped bolts inwardly toward each other upon projecting said horizontal bolt. 40
14. In a lock, a casing, a horizontal bolt slidably mounted therein, means for projecting said 45

- horizontal bolt, a pair of vertical U-shaped bolts each having an arm slidably mounted within said casing, a pair of symmetrical members each pivoted to said casing, said members having pin and slot connections with said horizontal bolt and operatively engaging said first mentioned arms of said U-shaped bolts for moving said U-bolts inwardly toward each other upon projecting said horizontal bolt. 80
15. In a lock, a casing having a front wall, top and bottom walls extending from said front wall, and end walls extending from said front wall, one of said end walls having an opening therein, a rear cover plate for closing the rear of said casing and attached to said casing, a horizontal bolt slidably mounted within said casing and adapted to be moved through said opening in said end wall, a vertical bolt slidably mounted within said casing and extending therefrom, said cover plate having a pin projecting into said casing, and a member pivoted to said pin and having portions operatively engaging said horizontal and vertical bolts, and means for causing sliding movement of said horizontal bolt to simultaneously move said vertical bolt. 90
16. In a lock, a casing open at the rear thereof, a rear cover plate attached to said casing, a bolt slidably mounted within said casing and having a pin projecting toward said rear cover plate, a second bolt mounted within said casing and movable in a direction transverse to the movement of said first bolt and having a pin portion projecting toward said rear cover plate, said cover plate having a pin portion projecting into said casing, and a flat plate having an opening receiving the pin portion on said cover plate, and slots receiving the pin portions of said bolts. 105
